US0D1031993S

(12) **United States Design Patent** (10) **Patent No.:** **US D1,031,993 S**
(45) **Date of Patent:** **** Jun. 18, 2024**

(54) **BREAST PUMP BOTTLE**

(71) Applicant: **Chiaro Technology Limited**, London (GB)

(72) Inventors: **Jonathan O'Toole**, Bristol (GB); **Andrew Carr**, Edinburgh (GB); **Adam Rollo**, London (GB)

(73) Assignee: **Chiaro Technology Limited**, London (GB)

(**) Term: **15 Years**

(21) Appl. No.: **29/874,181**

(22) Filed: **Apr. 14, 2023**

Related U.S. Application Data

(60) Continuation of application No. 29/836,874, filed on Apr. 29, 2022, now Pat. No. Des. 987,066, which is a division of application No. 29/672,048, filed on Dec. 3, 2018, now Pat. No. Des. 954,933.

(30) **Foreign Application Priority Data**

Jun. 1, 2018 (EM) 005292703

(51) **LOC (14) Cl.** **29-02**

(52) **U.S. Cl.**

USPC **D24/109**; D24/121

(58) **Field of Classification Search**

(57) **CLAIM**

The ornamental design for a breast pump bottle, as shown and described.

DESCRIPTION

FIG. 1 is a front perspective view of a breast pump bottle showing the claimed design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a rear perspective view thereof.

1 Claim, 8 Drawing Sheets
